(57) **CLAIM**

The ornamental design for a diatomite faucet mat, as shown and described.

DESCRIPTION

FIG. 1 is a top perspective view of a diatomite faucet mat, showing my new design.

FIG. 2 is a top view thereof.

FIG. 3 is a bottom view thereof.

FIG. 4 is a left side view thereof.

FIG. 5 is a right side view thereof.

FIG. 6 is a front view thereof; and,

FIG. 7 is a rear view thereof.

The broken lines are for illustrative purposes for features of the diatomite faucet mat that form no part of the claimed design.

1 Claim, 7 Drawing Sheets
